CLAIM

The ornamental design for a roll cutter, as shown and described.

DESCRIPTION

FIG. 1 is a perspective view of a roll cutter showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is another perspective view thereof;

FIG. 8 is a front perspective view thereof showing an operating state; and,

FIG. 9 is a rear perspective view thereof showing the operating state.

The broken lines in the drawings are for the purpose of illustrating unclaimed portions of the roll cutter and form no part of the claimed design.
